United States Patent Office

Des. 204,165
Patented Mar. 22, 1966

204,165

JUG

Willard F. Meyers, Toledo, Ohio, assignor to Owens-Illinois Glass Company, Toledo, Ohio, a corporation of Ohio

Filed Apr. 1, 1965, Ser. No. 84,548

Term of patent 14 years

(Cl. D58—5)

FIG. 1

The dominant feature of my design resides in portions shown in full lines.

I claim:

The ornamental design for a jug, substantially as shown and described.
